UNITED STATES PATENT OFFICE.

THOMAS L. BOYCE, OF SYRACUSE, NEW YORK, ASSIGNOR TO NATIONAL CHEMICAL AND MANUFACTURING COMPANY, OF SYRACUSE, NEW YORK, A CORPORATION OF ARIZONA.

APPARATUS FOR CLEANING OR REMOVING PAINT FROM SURFACES.

Application filed August 24, 1922. Serial No. 584,162.

To all whom it may concern:

Be it known that I, THOMAS L. BOYCE, a citizen of the United States of America, of Syracuse, in the county of Onondaga, in the State of New York, have invented new and useful Improvements in Apparatus for Cleaning or Removing Paint from Surfaces, of which the following, taken in connection with the accompanying drawings, is a full, clear, and exact description.

This invention relates to certain improvements in apparatus for cleaning or removing paint from surfaces.

The object of the invention is to produce an efficient apparatus for that purpose.

The present common apparatus used for substantially this purpose comprises an open-top tank or vat into which live steam is introduced for heating a large quantity of liquid contained in the vat. This apparatus is satisfactory so far as the heating is concerned, but where it is necessary to maintain a chemical of substantially constant proportion or water content, this method of heating is impractical for the reason that the steam coming in contact with the chemical condenses, and is constantly adding water to the chemical, thereby weakening it, and making it necessary to constantly add additional chemical in order to maintain the proper consistency.

In the method of this invention, the heating fluid, such as steam, does not come in contact with the chemical, and a forced circulation of the chemical is maintained independent of the steam or other heating fluid, and the atomization of the chemical is effected by means of pressure, and atomizing devices such as spray nozzles of suitable construction for that purpose.

The particular features of this invention reside in this circulation, agitation and the maintenance of pressure upon the chemical, all of such a character and so effected that the chemical is maintained in proper condition and consistency, and is forced from the circulating system to the atomizing devices by the maintained pressure.

Other objects and advantages relate to the details of construction of the apparatus, all as will more fully appear from the following description, taken in connection with the accompanying drawings, in which:

Figure 1 is an elevation of an apparatus of my invention. 55

Figure 2 is a longitudinal sectional view of the heater.

Figure 3 is an end view of the heater.

Figure 4 is a sectional view on line 4—4, 60 Figure 2.

The apparatus comprises a source for supplying steam under pressure, such as the boiler —1— distributing steam thru pipe —2— to a tank —3— adapted to contain a cleaning fluid and to the heater —4— 65 through which the chemical circulates. The steam entering the cleaning chemical tank —3— exerts pressure upon the surface of the same, and will cause the chemical to escape or flow outwardly through the pipe —44— to the discharge nozzle —5— of any suitable construction, and which may be associated with flexible hoses thereby permitting easy distribution of the cleaning chemical over the desired surface. The 70 atomization of this cleaning chemical from the nozzles —5— may be effected by steam under pressure escaping from the heater —4— through pipe —7— in communication therewith, and uniting with the cleaning 75 chemical line —44— at the union —8—.

Another portion of the steam from the heater —4— passes through pipe —9— to operate the pump apparatus —10—, the inlet pipe —11— of which pump is in communication with the vat —12— which contains the paint removing chemical. This chemical is drawn out through pipe —11— and is forced under pressure through pipe —23— into the heater —4— which heater 90 may, as shown in the drawing, be of substantially cylindrical form, and includes suitable internal heads —13— and —14— near its opposite ends, which heads are penetrated respectively by the opposite ends of a 95 series of tubes —15— through which the removing chemical flows and around which the live steam circulates for heating the chemical during its passage through the pipes. The pipe —23— communicates with one end of the heater exterior of the header —13— while the discharge pipe —16— communicates with the opposite end exterior of the header —14—, so as to form a closed chamber 100 within which the live steam circulates without contact with the paint removing chem-

105

ical. The pipe —16— leads back to the vat —12— and the chemical circulating under pressure through the system described and returning to the vat, effects a desired agitation of the chemical in the vat to maintain it in proper condition for effective use.

The pipe —16— is provided with a valve —17— for throttling the flow of the chemical through the pipe sufficiently to cause it to rise or flow out through the pipe —18— to one or more distributing pipes —19— which may, as shown, terminate in flexible hoses —20— and pressure spray nozzles —21— of any known or desired form for atomizing the chemical under the maintained pressure. The pipe —16— preferably includes an air bell —22— of suitable size and capacity to absorb or substantially absorb the pulsations of the pump in drawing the discharge from the vat —12— and discharging it under pressure back into the vat after it has been heated, and by throttling the line —16— through the medium of valve —17— sufficient of the heated chemical will be caused to flow through the chemical line —18— to adequately supply the pressure spray nozzles —21—.

Any suitable steam pressure may be maintained in the system and it is found that the maintenance of substantially 100 pounds of pressure in the boiler will produce substantially the same pressure throughout the entire system including the chemical lines —44— and —18—.

It will be noted that with this apparatus, the paint removing chemical is not distributed over the surface to be treated by either steam or air, but is atomized under pressure by means of suitable pressure spray nozzles and the removal of the paint is due to the action of the chemical, the excessive heat and the force with which the chemical is applied. The heating of the chemical is effected without contact with steam, and its constant agitation is maintained by the chemical passing from the heater under pressure back into the vat, while at the same time by the use of the same pressure, the required amount of the chemical is forced through the chemical line —18— to the nozzles —21—.

The heating of the chemical in heater —4— is effected by the use of substantially dry steam and there is little condensation in the steam lines due to the fact that any water drawn from the boiler —1— by the escaping steam escapes through connection

—24— into the tank —3— while the substantially dry steam continues through the steam line to the heater —4—.

Altho I have shown and described a specific apparatus and parts thereof as illustrative of a perhaps preferred embodiment of my invention, I do not desire to limit myself to the exact construction or arrangement or to the details of construction or form of the parts thereof, as various changes may be made in each without departing from the invention, as set forth in the appended claims.

I claim:

1. An apparatus of the class described comprising a source of steam, a steam line connecting said source with a tank adapted to contain a cleaning chemical and with a heater through which a paint removing chemical is adapted to circulate, a vat for containing a paint removing chemical, a circulating system in connection with the vat and including the heater connected to said steam line, means for causing the paint removing chemical to circulate through said system under pressure and an atomizing device adapted to be brought into communication with said system.

2. An apparatus of the class described comprising a vat adapted to contain a paint removing chemical, a circulating system in connection with said vat and including a heater, a circulating system for heating fluid through said heater unconnected to the circulating system for the chemical, a pump in the chemical circulating system, and means of communication between the pump and the circulating system for the heating fluid through said heater.

3. An apparatus of the class described, comprising a vat adapted to contain a paint removing chemical, a chemical circulating system in connection with said vat and including a heater, a circulating system for heating fluid through said heater unconnected to the circulating system for the chemical, a pump in the chemical circulating system, means of communication between the pump and the circulating system for the heating fluid through said heater, and an atomizing device adapted to be brought into communication with the circulating system for said chemical.

In witness whereof I have hereunto set my hand this 23 day of August, 1922.

THOMAS L. BOYCE.
